CLAMP-AROUND AMMETER-VOLTMETER

Toshihiko Sakow, Fort Lee, N.J., assignor to Mail Manufacturing Corporation, Bethpage, N.Y., a corporation of New York

Filed Nov. 13, 1969, Ser. No. 20,060

Term of patent 14 years

Int. Cl. D10—10

U.S. Cl. D26—1

FIG. 1

FIG. 2

FIG. 3

FIG. 4

FIG. 5

FIG. 6

FIG. 1 is a front elevational view of a clamp-around ammeter-voltmeter showing my new design:

FIG. 2 is a right side view thereof;

FIG. 3 is a top plan view thereof;

FIG. 4 is a rear view thereof;

FIG. 5 is a left side view thereof; and

FIG. 6 is a bottom plan view thereof.

I claim:

The ornamental design for a clamp-around ammeter-voltmeter, as shown and described.
